COMBINED CLIP DISPENSER AND PENCIL HOLDER

Robert M. Leedy, 7 Martindale Road,
Short Hills, N.J. 07078

Filed Nov. 19, 1973, Ser. No. 417,278

Term of patent 14 years

Int. Cl. D19—02

U.S. Cl. D19—75

FIG. 1

FIG. 2

FIG. 3

FIG. 4

FIG. 1 is a perspective view of a combined clip dispenser and pencil holder showing my new design;

FIG. 2 is a top plan view thereof;

FIG. 3 is a perspective view of another embodiment of the combined clip dispenser and pencil holder shown in FIG. 1 wherein the pencil holder is shown at a flat side; and

FIG. 4 is a top plan view thereof.

The undisclosed sides of the combined clip dispenser and pencil holder are plain and unornamented.

I claim:

The ornamental design for a combined clip dispenser and pencil holder, as shown and described.
